CLAIM

The ornamental design for vehicle seat, as shown and described.

DESCRIPTION

FIG. 1 is a top, right perspective view of my new vehicle seat design;

FIG. 2 is a top plan view of my new vehicle seat design;

FIG. 3 is front elevation view of my new vehicle seat design;

FIG. 4 is a rear elevation view of my new vehicle seat design;

FIG. 5 is a right elevation view of my new vehicle seat design;

FIG. 6 is a left elevation view of my new vehicle seat design;

FIG. 7 is a right elevation view of my new vehicle seats design shown with the right-hand seat reclined and shifted forward and with the center portion folded forward and shifted forward;

FIG. 8 is a top plan view of my new vehicle seats design shown with the right-hand seat reclined and shifted forward and with the center portion folded forward and shifted forward. A top plan view of a further vehicle seat, located rearward of vehicle seats according to my new vehicle seats design, is shown in phantom. The design of the reclined right-hand seat flows into the design of the further vehicle seat; and,

FIG. 9 is a right, front perspective view of my new vehicle seats design. A right, front perspective view of a further vehicle seat, located rearward of vehicle seats according to my new vehicle seat design, is shown in phantom. As in FIG. 8, the right-hand seat reclined and shifted forward and with the center portion folded forward and shifted forward and the design of the reclined right-hand seat flows into the design of the further vehicle seat.
